UNITED STATES PATENT OFFICE.

WILLIAM H. DOUGLAS, OF BELLEVILLE, NEW JERSEY.

DESIGN FOR A FRONT-AXLE HOUSING FOR VEHICLES.

42,317.

Specification for Design.

Patented Mar. 19, 1912.

Application filed October 10, 1911. Serial No. 653,959. Term of patent 7 years.

To all whom it may concern:

Be it known that I, WILLIAM H. DOUGLAS, a citizen of the United States, and resident of Belleville, in the county of Essex and State of New Jersey, have invented a new, original, and ornamental Design for a Front-Axle Housing for Vehicles, of which the following is a specification, reference being had to the accompanying drawing, forming part thereof.

Figure 1 is a plan view of a front axle

housing for vehicles, showing my new design, Fig. 2 is a front view of the same, and Fig. 3 is a side view of the same.

I claim:

The ornamental design for a front axle housing for vehicles, as shown.

WILLIAM H. DOUGLAS.

Witnesses:

F. GEORGE BARRY,
HENRY C. THIEME.
